CLAIM

The ornamental design for an agricultural and forestry hydraulic crusher machine for coupling to skid steer loaders as shown and described.

DESCRIPTION

The patent or application file contains at least one drawing executed in color. Copies of this patent or patent application publication with color drawing(s) will be provided by the Office upon request and payment of the necessary fee.

1. Agricultural and forestry hydraulic crusher machine for coupling to skid steer loaders

1.1 : Front

1.2 : Front perspective

1.3 : Right

1.4 : Bottom

1.5 : Left

1.6 : Top

1.7 : Back

The characteristics of the designs for which protection is claimed include the shape, configuration and ornamentation of an agricultural and forestry hydraulic crusher machine for coupling to skid steer loaders.
